FABRIC

Joseph Rowland Wynde and Harold Arthur Swift,
Spondon, near Derby, England, assignors to Cel-
anese Corporation of America, a corporation of
Delaware

Application October 22, 1938, Serial No. 236,394
In Great Britain March 15, 1938

1 Claim. (Cl. 139—421)

This invention relates to fabrics and particularly to fabrics having a puckered effect obtained by the inclusion therein of elastic yarn.

According to the present invention an elastic fabric comprises warp threads and weft threads of an inelastic character, and also weft threads of an elastic character woven into the fabric at intervals among the inelastic weft threads, the design of the fabric and the disposition of the elastic weft threads in said design being such that said elastic weft threads lie on or near the rear face of the fabric. Thus for example the design of the fabric may be such that the warps, controlled by a multi shaft dobby, are so actuated that when an elastic weft is introduced the warps of one shaft only pass to the rear of the elastic weft, so that the elastic weft is incorporated in the fabric and at the same time the majority of the warps, controlled by the remaining shafts, pass to the front of the elastic weft and conceal it from the front of the fabric.

During the weaving of the fabric, the elastic weft threads are in an extended condition, either by being woven under tension or by reason of a content of size or similar material applied to them when under tension so as to hold them in an extended condition. Consequently when the weft threads are allowed to relax from their extended condition, either by the relaxation of tension on the fabric or by the removal of the size holding them in their extended condition, the contraction of the elastic wefts causes the fabric to become attractively puckered.

The fabric may also contain elastic yarn in the warps, so that in addition to the contraction weftwise produced by the inclusion of the elastic weft there is also a warpwise contraction of the fabric. For example, if the spacing of the elastic warps is substantially equal to that of the elastic wefts the contraction of the fabric produces puckered areas in square sections of the fabric bounded by the elastic warps and wefts. In weaving the fabric with elastic warps it is generally convenient to carry the elastic warp threads on a separate beam. Where the elastic warps are to be woven under a substantial degree of tension the warp beam carrying them may conveniently be provided with a positive let-off motion, feeding the warps under tension to the fell of the fabric at a definite rate.

The elastic wefts may be inserted at uniform intervals in the length of the fabric, or at different or irregular intervals. Further, the elastic wefts may be laid in as single picks, for example by the use of a pick-and-pick loom or they

5 may be laid in as groups, e. g. in pairs by means of an ordinary two-box loom. In order to ensure that the elastic weft is laid at a substantially even tension throughout the length of the fabric it is advisable to change an exhausted pirn from the shuttle containing the elastic weft only when the shuttle containing the non-elastic weft is in operation. Thus in a two-box loom the elastic weft is used in the shuttle occupying the top box and the loom is stopped specially for the purpose of changing the pirn when the bottom box, containing the shuttle of non-elastic weft is in operation.

10 A fabric according to the present invention will now be described in greater detail with reference to the accompanying drawing in which—

Figure 1 is a diagrammatic view of the back of the fabric showing the arrangement of the elastic and inelastic yarns therein;

Figure 2 is a diagrammatic section on the line 2—2 of Figure 1;

Figure 3 is a diagrammatic section on the line 3—3 of Figure 1; and

Figure 4 is a view on a smaller scale of the 15 face of the fabric showing the puckered effect.

The fabric is of the character of an 8-shaft warp satin fabric having warp threads 1 and weft threads 2 woven together in the manner characteristic of such a fabric. In addition to the warp threads 1, and at intervals of about one 20 inch in the warp are included additional warp threads 3 of an elastic character, the warp threads 3 being fed from a separate warp beam and controlled by a separate shaft on the loom.

25 The warp threads 3 do not partake of the usual movement of the warp threads in an 8-shaft satin but are shedded as in a plain woven fabric, passing alternately over and under successive weft threads 2. The warp threads 3 are not substituted for inelastic warp threads 1 but are inserted in addition thereto, so that the 8-shaft satin pattern is complete in the warp threads 1.

30 Among the weft threads 2 there are inserted at intervals pairs of wefts, indicated at 4, having an elastic character. The weft threads 4, unlike the warp threads 3, take their place as weft threads in the 8-shaft satin weave, being substituted for inelastic weft threads 2. They are inserted at intervals of about $\frac{1}{2}$ inch in the 35 length of the fabric.

40 It will be seen that by the movement of an 8-shaft satin weave, each elastic weft thread 4 is bound into the fabric at the back by the warp threads of one shaft only, that is to say by $\frac{1}{2}$ of the warp threads 1. The remaining $\frac{1}{2}$ of the

warp threads 1 are passed in front of the weft thread 4. By these means the elastic picks 4 are caused to lie at the rear of the fabric, as shown in Figs. 2 and 3, and are not displayed on the face thereof. The elastic warp threads 3, by being plain woven in the fabric do not, like the remaining warp threads 1, lie mainly on the face of the fabric but are also, like the elastic weft threads 4, pushed to the rear of the fabric. This occurs partly because they are held at the back 10 of the fabric by only one half of the weft threads 2 and 4 which themselves lie chiefly on the back of the fabric, and also because, the warp density in a satin fabric being high relatively to the weft density, the neighbouring warps 1 crowd the elastic warps 3 to the back. In this manner, therefore, the elastic warp threads 3, as shown in Figs. 2 and 3, are effectively concealed, like the elastic weft threads 4, from the face of the fabric.

As is shown in Fig. 4, the fabric produced puckers, when the elastic threads contract, so as to give a pattern of puckered rectangles each bounded by the elastic threads. The fabric pro-

duced in this manner is suitable for the production of women's bathing costumes. If desired the fabric may be printed while in an extended condition, the subsequent puckering coupled with the printing producing a very attractive effect.

Having described our invention what we desire to secure by Letters Patent is:

An elastic fabric comprising inelastic warp threads and inelastic weft threads woven together in a satin weave in which a small proportion only of the warp threads pass behind any given weft thread, additional weft threads having an elastic character being woven in at intervals along the length of the fabric with a 15 weave similar to the weave of the inelastic weft threads and having a thickness greater than the thickness of the fabric at points between the intervals at which said elastic weft threads are woven, and elastic warp threads additional to said inelastic warp threads being woven in a one and one weave with relation to all of the weft threads.
